U.S. Appl. No. 29/688,709, filed Apr. 24, 2019.

Primary Examiner — John R Yeh(74) *Attorney, Agent, or Firm* — Leydig, Voit & Mayer, Ltd.(57) **CLAIM**

The ornamental design for a sponge, as shown and described.

DESCRIPTION

FIG. 1 is a right-side view of a sponge showing a first embodiment of my new design;

FIG. 2 is a front view thereof;

FIG. 3 is a top-right-front perspective view thereof;

FIG. 4 is a bottom view thereof;

FIG. 5 is a right-side view of a sponge showing a second embodiment of my new design;

FIG. 6 is a front view thereof;

FIG. 7 is a top-right-front perspective view thereof; and, FIG. 8 is a bottom view thereof.

In each of the first and second embodiments, the left-side view is a mirror image of the depicted right-side view and the rear view is a mirror image of the depicted front view.
